TELEVISION RECEIVER

Arno Zillger, Narberth, Pa., assignor to National Television Corporation, Wilmington, Del., a corporation of Delaware

Application November 28, 1934, Serial No. 755,113
Renewed December 19, 1939

5 Claims. (Cl. 178—7.3)

This invention relates to television receivers and particularly to a receiver embodying the scanning apparatus shown and described in my application entitled "Television system," Serial No. 626,579, filed July 30, 1932.

One object of the invention is to provide a television receiver which is compact and in which all of the parts are easily accessible.

Another object of the invention is to provide a television receiver in which the amplifier and light source of the apparatus form one unit which is entirely independent of the moving scanning element.

Another object of the invention is to provide a television receiver in which the light source may be mounted in the radio receiver.

Another object of the invention is to provide an adjustable mounting for the television light source so that the picture may be straightened by adjusting the source.

Another object of the invention is to provide a television receiver with a large angle of view.

Other objects of the invention and objects relating particularly to the novel assembly of the various parts will be apparent as the description proceeds.

The invention is illustrated in the accompanying drawings in which:

Fig. 1 is a front elevational view of my improved receiver;

Fig. 2 is a sectional plan view taken on the line 2—2 of Fig. 1;

Fig. 3 is a sectional side elevational view of the receiver taken on the line 3—3 of Fig. 2;

Fig. 4 is a sectional side elevational view through the end of the receiver unit taken on the line 4—4 of Fig. 2 and showing the lamp and mounting therefor; and

Fig. 5 is a sectional elevational view of a portion of the lamp connecting means taken on the line 5—5 of Fig. 3.

In Fig. 1 is shown a cabinet 10 having a base 11 and a top 12. The cabinet is substantially rectangular in shape but has a curved corner 13 in which is provided an opening 14 through which the observer looks to view the picture. The opening 14 may be provided with a suitable transparent window 15 which may be made of glass or other transparent material and which may be held securely in place by the clips 16 on the inside of the cabinet wall. Inside of the cabinet are positioned two units: the scanning unit 17 and the receiving unit 18, the former on the left hand side of the cabinet behind the window 15

and the latter substantially filling the right hand side of the cabinet.

The scanning element comprises a motor 19 which may be of the synchronous type, if desired, or any other type provided with a synchronizing device, such as a phonic wheel, in order to insure a speed synchronous to that of the transmitting system. The motor may be mounted on suitable shock-absorbing feet 20 which in turn may be screwed on to the base 11 to secure the motor in position. Upon the motor shaft 21 is mounted a scanning drum 22 which may be similar to that shown and described in my above mentioned application or in my patent entitled "Scanning drum construction," No. 2,112,390, granted March 29, 1938.

In the latter application a plurality of plates 23 are mounted upon a sleeve with supporting discs 23 and 25 at each end thereof. The plates are triangular in the construction shown with one edge of each a reflecting surface, and the reflecting surfaces are arranged in a helix around the drum at spaced angular intervals. This scanning drum is secured on the motor shaft 21 by the nut 26, and a suitable guard 27 is positioned around the drum to prevent any one touching the drum from the rear while it is in motion. The vertical position of the drum is such that it comes directly in back of the window 15 so that it may be seen by an observer looking through the window from in front or from the side of the receiver.

The receiver unit 18 may comprise any type of radio receiver suitable for receiving a television signal as for instance a superheterodyne receiver having a plurality of tubes 30 which I may mount in a horizontal position as indicated and a plurality of variable condensers 31 which I may mount on a vertical shaft 32. A wheel 33 also mounted on the condenser shaft 32 may be arranged to align with an opening 34 in the front side of the cabinet 10 so that a portion of it protrudes through the front wall of the cabinet for manual rotation by the operator. The wheel is preferably knurled or serrated on its circumference to facilitate turning by hand and is large enough in diameter so that the receiving set may be readily tuned by rotating the wheel. I prefer to mount all of the power supply parts at the rear of the unit where they may be enclosed in a suitable shielding box 35. The transformer 36 is shown mounted on top and the rectifier tube 37 is shown at the left with the power output tube 38 adjacent to it.

A switch 39 is positioned on the front of the

receiver and aligns with an opening 40 in the front wall of the receiver so that it protrudes through the wall and may be operated from the front of the receiver. The switch 39 may control the motor 19 as well as the power supply for the receiver 18.

Just above the wheel 33 I may provide a second wheel 41 which aligns with and protrudes through an opening 42 in the front of the cabinet. This wheel 41 may be for the purpose of controlling the volume of the signal received and may be mounted on the shaft 42a of a suitable variometer 43 which is mounted upon a bracket 44. In addition to the variometer 43 I may provide a switch 43a for the purpose of giving the lamp an additional potential impulse for starting. This switch may be operated by the shaft 42a in the same manner that the current supply switch is mounted on the volume control shaft in a radio receiver and may have one terminal connected to ground on the chassis and the other connected to a wire 44a which leads to the bottom socket of the lamp to be hereinafter described.

At the left hand side of the receiver as viewed in Figs. 1 and 2 I provide a compartment 46 to hold the lamp 47 and a mirror 48 for directing the rays of the lamp towards the drum. The compartment has a rectangular cross-section with a length approximately that of the front to rear length of the receiver. The lamp is positioned at the rear of this compartment in a substantially vertical position while the mirror 48 is positioned at the forward end and is parallel to the axis of the lamp and arranged at such an angle as to throw the rays of the lamp towards the drum 22 through a suitable opening 49 in the wall of the compartment 46. The mirror 48 may be mounted on a suitable bracket 50 which is pivoted at 51 and is provided with an arcuate slot 52 and a cooperating screw 53 so that the angle of the mirror may be adjusted to give the proper illumination of the drum.

The lamp 47 may be made similar to the construction shown and described in the application of John M. McKay, Serial No. 628,321, filed August 11, 1932, entitled "Television lamp and apparatus." Such a lamp comprises a transparent tubular portion 54, from which the light issues to the drum, and enlarged bulbs 55 and 56 at each end thereof. The lower bulb 56 is provided with a screw base 57 with the central terminal 58 similar to the screw base of an electric light bulb and connected to the electrode 59 within the bulb. The outer terminal 60 is shown connected to a shield 61 which partly surrounds the tubular member 47 and may in the present instance be formed integral therewith as by being cemented to the glass. The terminal 58 makes contact with a terminal 62 in the socket 63, which is connected to the output of the receiver, while the threaded sleeve 64 in the socket may be connected to the switch 43a on the receiver by the wire 44a so that this terminal may be connected to ground on the chassis when the switch is closed.

The upper end of the lamp terminating in the bulb 55 is also provided with a cap 65 which may fit into a smooth-walled socket 66 which is preferably arranged to resiliently and frictionally grip the cap 65 so as to make good contact therewith. I may mount the socket 66 upon an insulating block 67 which is in turn supported upon a cover plate 68 which covers the top of this end of the compartment 46. The cover plate 68 may extend down on the sides of the

compartment to be secured in place by screws 69 and it may have a flange 70 extending downwardly inside of the compartment to cover or shield the upper bulb 55 so that it will not interfere with the operation of the scanning drum. Thus light which may be produced by the bulb 55 is prevented from reaching the drum.

The socket 63 is preferably mounted on a soft rubber base 71 so that it will be free to tilt in any direction to permit setting the lamp at a desired inclination. The socket 66 is also resiliently mounted with respect to the block 67 which is movable on the cover plate 68. In order to provide for movement of the block 67 I may provide holes 72 in the cover plate 68 through which may pass machine screws 73 which may be screwed into tapped holes in a ring 74 placed beneath the cover plate 68. The socket and block 67 may be shifted from side to side and then locked in position by tightening the screws 73 when the proper inclination is found.

From the above it will be seen that I have provided a television receiver which is compact and simple to construct and operate and in which there are two separate parts: the motor and drum, which forms one unit, and the receiver with the light source included, which forms the other unit. As the light source is mounted close to the amplifier there is a minimum of connecting leads and all of the connections may be covered and suitably shielded. The receiver may be readily tuned by means of the two discs 33 and 41, the former selecting the wave length and the latter controlling the volume of the signal. Inasmuch as the motor fits at a definite position in the cabinet and the light source is fixed in the receiving unit the adjustment of the light source with respect to the drum need not be changed when it is once determined and the receiving set may be removed from the cabinet to change tubes for instance, without interfering with this adjustment. The cabinet may be provided with a suitable back 75 which may have a series of openings therein to provide ventilation so that the various tubes will not become overheated.

Inasmuch as the drum and motor is positioned in the cabinet spaced from the viewing window 14 a great deal of the outside light is prevented from striking the drum and this is augmented by the decorative ribs 76 which are positioned above and below the window and which may be painted black if desired to eliminate reflection as much as possible. This makes it possible to use the receiver in broad daylight in a brightly lighted room but it is necessary to prevent direct light from striking the drum, as, for instance, from a table lamp.

While the window for viewing the television picture has been shown on the corner of the cabinet the invention is not to be limited to such a construction as the window and drum might be positioned at the center with the parts of the receiving unit distributed on each side of the drum. Owing to the nature of the helical drum it is possible to see a picture from various positions around the drum through a very wide angle. Hence if the window is at the center it may be considerably wider so as to give the same angle of view as where it is positioned at the corner.

A curved glass has also been shown for the window but it will be evident that a flat glass may be used for this purpose, or the glass may be entirely eliminated, if desired, although it is recommended for keeping dust away from the

mirror drum and for preventing any one from touching the drum while it is in motion.

Many modifications of the invention may be resorted to without departing from the spirit thereof and I do not therefore desire to limit myself to what has been shown and described except as such limitations occur in the appended claims.

What I claim is:

10 1. A television receiver comprising a radio receiving set, a compartment at one end of said set, a light source within said compartment and comprising a pair of spaced apart electrodes in an atmosphere of ionizable gas and separated by a relatively long small diameter tubular member to restrict the discharge to a line of light, said electrodes being connected to the output of said radio receiver, means to adjust the inclination of said light source, and a reflector adjustably positioned substantially parallel to said line of light to direct the rays therefrom outwardly through an opening in said compartment.

2. A television receiver comprising a radio receiver having a compartment at one end thereof, a tubular light source within said compartment, means to adjust the inclination of said light source, said light source being connected to the output of said radio receiver, a conducting member in close proximity to said tubular member and extending substantially the length thereof, switching means to connect said conductor to ground, and a reflector positioned within said compartment and adapted to direct the light from said source outwardly through an opening in said compartment.

3. A television receiver comprising a cabinet, a helical mirror drum rotatably mounted within said cabinet, a window in said cabinet so arranged that said drum may be observed from outside of said cabinet, a radio receiving unit within said cabinet, said unit having a compartment at one end thereof nearest to said drum, a tubular light source within said compartment and mounted substantially parallel to said drum, means to adjust the inclination of said light source, said light source being connected to the output of said radio

receiver, means to direct the light from said source through an opening in said compartment to said drum, a conductor positioned in close proximity to said light source and extending substantially the length thereof, and switching 5 means to connect said conductor to ground.

4. A television receiver comprising a cabinet, a window in said cabinet, a helical mirror drum positioned within said cabinet behind said window, a radio receiving unit positioned within said cabinet, a compartment in the end of said unit nearest to said drum, a tubular light source within said compartment and mounted substantially parallel to the axis of said drum, means to adjust the inclination of said light source, said light 10 source being connected to the output of said radio receiver, means to control the volume of the output of said receiver, a conductor positioned in close proximity to said tubular light source and extending substantially the length thereof, and 15 switching means associated with said volume control to connect said conductor to ground when said volume control is turned down.

5. A television receiver comprising a radio receiving set, a compartment at one end of said set, 25 a light source within said compartment and comprising a pair of spaced-apart electrodes in an atmosphere of ionizable gas and separated by a relatively small diameter tubular member to restrict the discharge to a line of light, said electrodes being connected to the output of said radio receiver, means to adjust the inclination of said light source, a reflector adjustably positioned substantially parallel to said line of light to direct the rays therefrom outwardly through an opening 30 in said compartment, a scanning device mounted outside of said receiving set and positioned so as to receive light rays passing outwardly through the opening in said compartment, said scanning device comprising a plurality of long narrow reflecting surfaces arranged side by side in a helix around an axis and having equal angular spacing therearound, and means to rotate said scanning device about the axis thereof at a predetermined 35 rate of speed.

ARNO ZILLGER.
